UNITED STATES PATENT OFFICE.

JULIUS TARR, OF PHILADELPHIA, PENNSYLVANIA.

SHIP LOADING OR COALING DEVICE.

SPECIFICATION forming part of Letters Patent No. 739,038, dated September 15, 1903.

Application filed April 23, 1903. Serial No. 153,929. (No model.)

To all whom it may concern:

Be it known that I, JULIUS TARR, a subject of the Emperor of Austria-Hungary, residing at Philadelphia, county of Philadelphia, and 5 State of Pennsylvania, have invented a certain new and useful Improvement in Ship Loading or Coaling Devices, of which the following is a specification.

My invention relates to a new and useful 10 improvement in apparatus for loading and unloading vessels, and is intended, primarily, for the purpose of coaling vessels while at sea, and has for its object to provide an apparatus which will be carried by the collier and 15 which apparatus may be connected with another vessel or to the land, so that coal may be transferred from one point to another, to be operated entirely from the vessel carrying the apparatus.

With these ends in view this invention consists in the details of construction and combination of elements hereinafter set forth and then specifically designated by the claims.

In order that those skilled in the art to 25 which this invention appertains may understand how to make and use the same, the construction and operation will now be described in detail, referring to the accompanying drawings, forming a part of this specification, in which—

Figure 1 represents my apparatus extending from a vessel to the land. Fig. 2 represents my apparatus as extended between two vessels; Fig. 3, a side elevation of the upper 35 portion of the boom and the traveler; Fig. 4, a plan view of the traveler; Fig. 5, a similar view to Fig. 3, showing the ratchet mechanism, trip, and the bucket in the position to descend or ascend; Fig. 6, a perspective view 40 of a portion of the mast of the vessel to which the apparatus is secured, showing the construction of the weight for keeping the cable upon which the traveler runs taut; Fig. 7, a plan view of one of the weights.

Upon the vessel which carries the apparatus is arranged a boom A, pivoted so as to swing on the pivotal point B. This boom is supported by a guy-rope or cable C, which extends from the upper end of the boom over 45 a pulley D on the mast and extends downward and is secured to the lower end of the mast in any suitable manner, as represented

at E. This guy-rope C is for the purpose of raising or lowering the boom, and there are guy-ropes or cables F extending from the upper end of the boom upon each side for the purpose of holding the boom against swinging and regulating its position.

G is a cable upon which the traveler H runs, and the outer end of this cable is designed to 60 be carried to the end of the vessel to be coaled or to a point upon the land and secured in any suitable manner; but this end of the cable must necessarily be secured at a point lower than the upper end of the boom, so that the 65 traveler will run downward upon an incline. The cable G extends over a pulley A', journaled upon the boom, and over a pulley I, journaled upon the mast, and to this end of the cable is secured a weight J, designed to 70 always keep the cable G taut, as the swaying and movement of the vessels will necessarily shorten and lengthen the cable, and this weight will always keep the cable taut, so that the traveler may be free to run upon the same. 75 The weight J consists of two upright rods J', secured together at the top and bottom by the cross-pieces J². The cable G is secured to the upper cross-piece.

K represents disks which form the weight. 80 Each one of these disks is provided with snap-hooks K' upon each side, which may be snapped upon the rods J'.

L is a rod extending vertically parallel with the mast and secured to the mast rigidly at 85 the top and bottom. This rod passes through the cross-pieces J² and guides the framework in its movement. The disk weights are slotted at the point K², so as to straddle this rod L when placed in the frame.

The traveler H consists of a framework in which are journaled the rollers M, which rest upon the cable G.

N is a drum journaled in the framework of the traveler.

O is a cable secured at one end to the framework of the traveler H, and this cable then passes downward around the pulley of a block P, then over a pulley Q, journaled in the framework of the traveler, and then passes 100 with one or more turns around the drum N and from there to a pulley R, secured to the boom, and from this pulley downward to a winding apparatus, such as a capstan or

steam-winches S, located upon the deck of the vessel carrying the apparatus. To the block P is secured a hook P', to which is suspended the bucket P², which conveys the coal or other material. Secured to the same shaft as the drum N is a ratchet-wheel T.

T' is a spring-pawl normally in engagement with the ratchet-wheel, and T² and T³ are levers pivoted to the framework, adapted to operate so as to raise the pawl from out of engagement with the ratchet-wheel.

U is a trip secured to the upper end of the boom, and this trip is arranged in such a position that when the traveler is forced against the boom this trip will depress the heel end of the lever T³, so as to raise the pawl T' out of engagement with the ratchet-wheel.

V is a spring-latch adapted to slide parallel with the boom and guided thereon, this latch having a beveled nose, and when the projection H', extending downward from the traveler, strikes this beveled surface it will depress the latch and pass behind the same, when the latch will spring back into its normal position, holding the traveler against the boom until released. At the lower end of the rod V', to which the latch is attached, is secured a rack V², which is adapted to be operated upon by the segmental gear V³, whereby the latch may be raised and lowered.

In operation after the outer end of the cable G has been secured to the land or another vessel and the traveler H is held by the latch V against the boom the bucket P² is lowered to the deck or hold of the vessel, and by slackening up on the cable O the bucket P² is allowed to be lowered, because when in this position the pawl T' is out of engagement with the ratchet-wheel T, thus allowing the ratchet-wheel to turn with a retrograde movement. After the bucket P² has been filled then by pulling upon the cable O the bucket is raised until stopped by the projection P³ on the block P coming in contact with the framework of the traveler. Then by manipulating the gear V³ the traveler is released and will commence to travel along the cable G by gravity, and as soon as it is clear of the trip U the spring-pawl T' will enter into engagement with the ratchet-wheel T and prevent any retrograde movement of the ratchet-wheel. Then by paying out the cable O the traveler will be allowed to descend along the cable G to its destination, and when this is reached the operator at that end can release the pawl T' by pulling the rope W and by still further paying out the cable O. The bucket then will be allowed to descend and can be emptied, and, the signal being given, the operator upon the vessel to which the apparatus is attached will begin winding up the cable O, which will first raise the bucket to the limit of its movement, and as the cable O continues to wind up the traveler H will be drawn along the cable G, and when it springs the latch V will be automatically locked in place and the pawl T' automatically removed from

the ratchet-wheel. Thus it will be seen that a very simple, complete, durable, and efficient apparatus is provided whereby vessels can be 70 coaled at sea, even in stormy weather, and can remain at a considerable distance from one another, so as to be in no danger of collision.

Of course I do not wish to be limited to the 75 exact construction here shown, as slight modifications could be made without departing from the spirit of my invention.

Having thus fully described my invention, what I claim as new and useful is— 80

1. In a device of the character described, a boom pivoted to the deck of the vessel, guy-ropes for adjusting and securing the boom in place, a cable secured at one end to another vessel or to the land, this end being secured at 85 a point lower than the upper end of the boom, said cable passing over a roller journaled in the upper end of the boom and also over a roller secured to the mast of the vessel, a weight suspended upon this end of the cable, 90 a traveler designed to travel along said cable, a cable secured to said traveler, a bucket or other receptacle suspended from said cable, said cable passing from the traveler over a pulley upon the boom downward to a winding 95 apparatus, means for releasing the bucket so as to allow the same to descend when it has reached its destination, as and for the purpose specified.

2. In a device of the character described, a 100 boom pivoted upon the deck of the vessel, guy-ropes for securing said boom in position, a cable, one end of which is secured to another vessel or to the land at a point lower than the upper end of the boom, the other end of said cable after passing through suitable pulleys on the upper end of the boom and the mast passing downward, a weight secured upon this end of the cable so as to always keep the cable taut, a traveler adapted to travel upon 105 this cable, a second cable secured at one end to the traveler, a block and pulley around which this cable passes, a pulley carried by the traveler over which the cable passes after passing around the block-pulley, a drum journaled in the traveler around which the cable passes with one or more turns, a pulley secured to the boom from which this cable passes from the drum, the other end of the cable being attached to a winding apparatus located 110 upon the deck of the vessel, a bucket or other receptacle suspended from the block and pulley, means for holding the drum against retrograde movement while traveling along the cable, means for automatically releasing the 115 drum when the traveler is in contact with the boom, and means for locking and releasing the traveler when in contact with the boom, as specified.

3. In a device of the character described, a 130 cable attached at one end to the vessel carrying the apparatus and at the other end to another vessel or a point upon the land at a lower point than the end upon the vessel,

- means for keeping said cable taut at all times, a traveler designed to travel upon said cable, a second cable attached at one end to the traveler, then passing downward and around 5 a pulley of a block, a pulley journaled in the traveler over which the cable then passes, a drum journaled in the traveler around which the cable then passes with one or more turns, a winding apparatus on the deck of the vessel 10 to which the apparatus is secured, the other end of this cable being attached to this winding apparatus, a bucket or other receptacle suspended from the block and pulley, a ratchet-wheel secured upon the same shaft 15 as the drum in the traveler, a spring-pawl adapted to normally engage the teeth of this ratchet-wheel so as to prevent the bucket from descending, means for automatically raising the pawl out of engagement with the ratchet-wheel when it has reached its destination, and means for automatically locking the traveler against return movement upon the vessel to which the apparatus is secured, and means for releasing the same, as specified. 20
- 25 4. In combination in a device of the character described, a cable extending from one point to another, a traveler designed to travel upon said cable, a second cable attached at one end to the traveler, a block and pulley 30 around which said cable passes, a bucket or other receptacle suspended from said block or pulley, a pulley carried by the traveler over which the cable then passes, a drum journaled in the traveler around which the cable then passes with one or more turns, a winding apparatus to which the other end of this operating-cable is attached, a ratchet-wheel secured upon the same shaft as the drum, a spring-pawl adapted to be always in 35 engagement with said ratchet-wheel while the traveler is traveling, means located at the starting-point of the traveler adapted to au-
- tomatically release the pawl from the ratchet-wheel so as to allow the bucket to descend to be filled when the operating-cable is slackened, and means for automatically locking the traveler against return movement, and means for releasing the same, as specified. 45
5. In a device of the character described, a cable, one end of which is attached to a vessel or a point upon the land, the other end of said cable passing around the pulley upon the vessel which carries the apparatus, said cable then passing downward, a weight secured to the lower end of this cable, said weight consisting of side rods, cross-pieces joining said side rods together at the top and bottom, disk weights provided with snap-hooks upon each side adapted to snap upon the side rods, a rod for guiding the weight in its movements, a traveler adapted to travel upon the cable, an operating-cable secured at one end to the traveler, a block and pulley around which the cable then passes, a bucket or other receptacle suspended from said block 60 or pulley, a pulley journaled in the traveler around which the cable then passes, said cable then passing around a pulley located upon the vessel carrying the apparatus, and from thence to a winding apparatus, means for clutching the operating-cable and preventing the descent of the bucket while the traveler is moving, and means located upon the operating vessel for automatically releasing this cable, and means for locking and releasing 65 the traveler to and from the operating vessel, as specified. 70
